CLAIM

The ornamental design for a padlock, as shown and described.

DESCRIPTION

FIG. 1 is a front perspective view of a front perspective view of a padlock showing our new design;

FIG. 2 is a rear perspective view thereof with shackle unlocked.

FIG. 3 is a front side elevation view thereof.

FIG. 4 is a back side elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a front perspective view of a second embodiment of the padlock;

FIG. 10 is a rear perspective view thereof with shackle unlocked.

FIG. 11 is a front side elevation view thereof.

FIG. 12 is a back side elevation view thereof.

FIG. 13 is a left side elevation view thereof.

FIG. 14 is a right side elevation view thereof.

FIG. 15 is a top plan view thereof; and,

FIG. 16 is a bottom plan view thereof.

The broken lines illustrate unclaimed portions and form no part of the claimed design.
